UNITED STATES PATENT OFFICE

127,272

DESIGN FOR A STATUETTE OR SIMILAR ARTICLE

Nicholas W. Hirsch, Philadelphia, Pa., assignor to Beverage Products Corporation, Philadelphia, Pa., a corporation of Pennsylvania

Application November 22, 1940, Serial No. 96,727

Term of patent 14 years

To all whom it may concern:

Be it known that I, Nicholas W. Hirsch, a citizen of the United States and a resident of Philadelphia, Pennsylvania, have invented a new, original, and ornamental Design for a Statuette or Similar Article, of which the following is a specification, reference being had to the accompanying drawing, forming part thereof, in which:

Fig. 2 is a rear view; and

Fig. 3 is a side elevation.

I claim:

The ornamental design for a statuette or similar article, substantially as shown.

NICHOLAS W. HIRSCH.
